(57) **CLAIM**

The ornamental design for a monitor and printer stand, as shown and described.

DESCRIPTION

FIG. 1 is a perspective view showing our new design for a monitor and printer stand;

FIG. 2 is a front view of the stand of FIG. 1;

FIG. 3 is a side view of the stand of FIG. 1, the opposite side view being a mirror image thereof;

FIG. 4 is top plan view of the stand of FIG. 1;

FIG. 5 is a bottom plan view of the stand of FIG. 1;

FIG. 6 is a rear view of the stand of FIG. 1; and,

FIG. 7 is a bottom perspective view of the stand of FIG. 1.

The broken lines are for the purpose of illustrating portions of the stand and form no part of the claimed design.
